[57] CLAIM

The ornamental design for a container closure, as shown and described.

DESCRIPTION

FIG. 1 is a side elevational view of a container closure showing our new design;

FIG. 2 is a top plan view thereof;

FIG. 3 is a cross-sectional view thereof, taken on line 3—3 of FIG. 4; and

FIG. 4 is a bottom plan view thereof.

FIG. 1

FIG. 2
